UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,067, dated July 18, 1882.

Application filed June 5, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is shown in the accompanying photographic illustration.

The design is composed of the large bouquet B, composed in part of blossoms on elongated stalks and elongated leaves, an architectural figure, C, surmounted by foliage, a bouquet, D, composed of a central group of roses and diverging foliage, and an arbor, E, over the bouquet D. 15

I claim—

The design for a carpet, substantially as shown and described.

In testimony whereof I have signed my name to this specification, in the presence of two 20 subscribing witnesses, this 29th day of May, 1882.

THOMAS J. STEARNS.
